No. 674,075.

W. J. CARROLL.

Patented May 14, 1901.

TRUNK.

(Application filed Sept. 17, 1900.)

(No Model.)

UNITED STATES PATENT OFFICE.

WILSON JOHN CARROLL, OF CRIPPLECREEK, COLORADO.

TRUNK.

SPECIFICATION forming part of Letters Patent No. 674,075, dated May 14, 1901.

Application filed September 17, 1900. Serial No. 30,292. (No model.)

To all whom it may concern:

Be it known that I, WILSON JOHN CARROLL, a citizen of the United States, residing at Cripplecreek, in the county of Teller and State 5 of Colorado, have invented a new and useful Trunk, of which the following is a specification.

The present invention relates to improvements in trunks; and the object thereof is to 10 provide an improved follower arranged within the trunk-body and adapted to be secured at different distances from the bottom, whereby any quantity of clothing carried in the trunk can be tightly packed in place to prevent its disarrangement and wrinkling.

In order that the invention may be readily understood by those skilled in the art, the preferred form is shown in the accompanying drawings and described in the following specification, of which said drawings form a part; but it will be understood that the construction shown and described is capable of modification and change within the scope of the appended claims.

25 In the drawings, Figure 1 is a perspective view of a trunk with the lid thrown back and showing the improved follower applied. Fig. 2 is a vertical longitudinal sectional view of the trunk-body. Fig. 3 is a top plan view. 30 Fig. 4 is an enlarged detail horizontal view on the line xx of Fig. 2.

Similar numerals of reference designate corresponding parts in the several figures of the drawings.

35 As shown in the drawings, the numeral 10 designates the body of an ordinary trunk, having a hinged cover 11 and provided contiguous to the upper edges of its inner end walls with the horizontal supporting-cleats 12, 40 upon which the usual tray or till rests. These elements form no part of the present invention, but are shown in order that the application thereof may be more readily understood.

The invention comprises a follower attachment mounted between the bottom of the trunk and the supporting-cleats 11 and having novel means for securing it upon the articles placed within the body of the trunk.

In carrying out this invention, as shown, a 50 flat horizontal follower 13 is provided, which fits snugly within the trunk-body and conforms, substantially, to the shape of the same.

This follower is provided upon its upper face with a handle 14, which preferably comprises a looped piece of flexible material that will 55 fold flat upon the follower when not in use.

In order to secure the follower 13 upon the articles placed beneath the same, vertical guide-strips 15 are provided upon the inner end walls of the trunk-body, said strips being each 60 provided with a vertical row of openings 16, which are adapted to be engaged by spring-catches of the presser-bars hereinafter described. The strips extend from the bottom of the trunk-body nearly to the tray-support- 65 cleats 11, leaving a space between the latter and the ends of said strips to permit the ready application and removal of the presser-bars. These guide-strips are preferably T-shaped in cross-section, the projecting flanges 15^a being secured to the respective walls of the trunk-body, thus forming the oppositely-arranged grooves 17. Slidably mounted upon these guide-strips 15 are presser-bars 18, which extend across the end portions of 70 the follower 13, parallel to the end walls, to which they are thus secured, and are each provided with a spring-catch 19, that is adapted to engage the openings 16. These presser-bars are each provided on one side with a T- 75 shaped notch, through which passes the guide-strips, the lugs 20, formed by said notch, fitting in the oppositely-arranged grooves 17 of the guide-strip. By this means the presser-bars have a free vertical movement, but are 80 held to the respective ends of the trunk-body.

The spring-catches 19 each preferably comprises a bowed rod, one end of which is headed, as at 21, said headed end fitting in a socket 22 in the wall of the presser-bar opposite to 90 the T-shaped notch, to one side thereof, and having a spring 23 coiled around the shank of the same. A retaining-plate 24 is arranged over the mouth of the socket, and the rod passes through this plate, which thus forms 95 a bearing against which one end of the coiled spring 23 rests. The opposite end of the rod passes directly across the upper face of the presser-bar, normally projecting into the plane of the T-shaped slot and forming a bolt 25, 100 which engages in the openings 16.

In operating the device the articles having been placed in the bottom of the trunk the follower is placed over the same. The presser-

bars are then mounted upon the locking-strips, with the spring-catches thrown out of engagement, as shown in dotted lines in Fig. 3. The bars can thus be moved freely without interference from said catches. When the follower has been tightly pressed down upon the contents, the spring-bolts are swung into operative position and will secure the follower in place, the springs holding the bolts in the openings, so that there is no danger of their accidental displacement by jarring or tilting the trunk. It will thus be seen that a follower is provided that can be adjusted to the varying quantity of clothing carried in a trunk and that will securely hold the same in place. While the device has been described as being applicable to trunks, it will be evident to those skilled in the art that it may be readily applied with equal advantage to other receptacles.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim to be new, and desire to secure by Letters Patent, is—

1. The combination with a receptacle, of vertically-arranged substantially T-shaped guide-cleats secured to opposite interior walls of the receptacle and intermediate the ends

of said walls, a follower adjustably arranged within the receptacle, independent presser-bars arranged adjacent to the opposite interior walls of the receptacle and each having a substantially T-shaped notch intermediate its ends which receives the guide-cleat of the adjacent wall, whereby said bar is slidably interlocked, said presser-bars being arranged to bear upon the follower, and locking means carried by the presser-bars and arranged to engage the guide-cleats to hold said bars against movement.

2. The combination with a receptacle, of a follower adjustably arranged within the receptacle, and means for securing said follower against movement, said means including a bolt having substantially parallel arms, one of which is slidably secured to said means, the other being arranged to engage a portion of the receptacle.

3. The combination with a receptacle, of a follower arranged within the receptacle, a presser-bar also arranged within the receptacle upon the follower, and a substantially U-shaped bolt, one of the arms of which is pivotally and yieldingly secured to the presser-bar, the other arm being arranged to engage a portion of the receptacle to hold the bar and follower against movement.

In testimony that I claim the foregoing as my own I have hereto affixed my signature in the presence of two witnesses.

WILSON JOHN CARROLL.
